UNDERFEED RIVETING MACHINE

Loyd A. Ward, Jackson, Mich., assignor to Tomkins-Johnson Company, Jackson, Mich., a corporation of Michigan

Application February 25, 1938, Serial No. 192,467

20 Claims. (Cl. 78—48)

This invention relates to riveting machines and the like and more particularly to such machines of the underfeed type.

In certain types of riveting machines it is desirable that the upsettable member be automatically positioned on the anvil in proper alignment with the set to permit the work to be disposed over the upsettable member before the heading up thereof. The present invention contemplates the provision of a riveting machine or the like for automatically presenting an upsettable member for receiving the work, the machine being arranged to quickly, accurately and efficiently present and feed upsettable members as rapidly as may be desired, the upsettable members being fed to a position beneath the set and moved upwardly by a vertically reciprocable anvil into cooperating relation with the set.

An object of the invention is to provide an underfeed riveting machine or the like.

Another object of the invention is to provide a riveting machine or the like having an anvil reciprocable along the vertical axis of the set.

A further object of the invention is to provide a riveting machine or the like having an anvil movable vertically toward and away from the set, arranged to receive an upsettable member at the lower portion of its reciprocating path.

A still further object of the invention is to provide a riveting machine or the like having a vertically reciprocable anvil wherein the movement of the anvil is coordinated with the feeding of the upsettable members.

A still further object of the invention is to provide a riveting machine or the like of the character set forth having a movable anvil and coordinated rivet feeding and anvil movement, which is semi-automatically controlled.

These and other objects will be apparent from the following specification when taken with the accompanying drawing, in which

Fig. 1 is a partial vertical section disclosing the details of the construction of the machine comprising the invention.

Fig. 2 is a section on the line II—II of Fig. 1, showing a detail.

Fig. 3 is a section on the line III—III of Fig. 1, showing the feeding chute, and

Fig. 4 is a view similar to a portion of Fig. 1, disclosing the anvil and its associated structure in retracted position.

Referring particularly to the drawing, the reference character 1 indicates a frame. Mounted for reciprocatory movement in the frame 1 is a ram 2, to which is secured a set 3. Mounted

directly beneath the set 3 is a vertically reciprocable anvil 4 slidably disposed in an anvil guiding member 5. The anvil guiding member 5 is secured to a head 6 connected to the frame 1 in any suitable manner. Vertical displacement of the head 6 with respect to the frame 1 due to the upsetting thrust is resisted by a key 7.

The anvil 4 is shown in Fig. 1 in its uppermost or active position and is maintained there by a follower 8 swingable about a pivot 9. The follower 8 is moved upwardly about the pivot 9 by a cam 10 slidable in a slideway 11 in the housing 12 and a portion of the head 6. The housing 12 is mounted on the frame 1 and also supports the pivot 9. The cam 10 is reciprocated in its slideway 11 by a piston 13 movable in a cylinder 14, the cylinder 14 being secured to the housing 12 in alignment with the slideway 11.

The anvil 4 has depending therefrom a rod 20, the lower portion of which projects from the bottom of the head 6 and has disposed thereon a helical spring 21 held on the rod by a stop 22. Thus, the spring 21 acting against the stop 22 and the lower side of the head 6 continuously urges the anvil 4 downwardly. The rod 20 extends through a channel 23 in the follower 8, as shown particularly in Fig. 2, and through a similar channel in the cam 10.

A horizontal feeding channel 24 projects through an opening 25 in the side of the anvil guide 5 and at the opposite end communicates with a feeding chute 26, as shown in Fig. 3. The feeding chute may be supplied with upsettable members either manually or by an automatically acting hopper. A feeding plunger 27 is slidably arranged in a slideway 28 in a housing 29 secured to the frame 1. Movement of the feeding plunger 27 in one direction is limited by the adjusting screw stop 30. Movement is imparted to the feeding plunger 27 by a rocker arm 31 oscillatable about a pivot 32 mounted in the housing 29, and movement is imparted to the rocker arm 31 by a plunger 33 slidable in a slideway 34 in the housing 29. Openings 35 and 36 in the plungers 27 and 33, respectively, provide operating connections with the rocker arm 31.

In operation of the invention, a controlling device of the character disclosed in the copending patent applications of Harold A. Tomkins, Serial No. 53,404, filed December 7, 1935, and Harold A. Tomkins et al., Serial No. 86,106, filed June 19, 1936, is employed, although other controlling devices may be used if desired. As shown, the anvil 4 has disposed thereon an upsettable member 40, which may be a rivet of any desired character,

a clinch nut, or the like. The work is disposed over the upsettable member 40 and the machine operated in a conventional manner to move the set 3 downwardly to upset the upsettable member 40 to secure it to the work. As shown in Fig. 1, the follower 8 and the cam 10 back up the anvil 4 to provide a solid foundation to the bottom of the head 6.

The control device disclosed in the aforesaid patent applications is of the character wherein the actuation of a manual push button valve releases compressed air to move a distributing valve to direct compressed air to the cylinder 14 from a source of supply. When the manual valve (not shown) is operated, compressed air from a suitable source is admitted through the inlet 41 and the port 42 to the left end of the cylinder 14 to urge the piston 13 to the right. The piston 13 is connected to the cam 10 by a piston rod 43. Thus, movement of the piston 13 to the right moves the cam 10 to the right, with the result that due to the action of gravity and of the spring 21 the follower 8 and the anvil 4 both move to their lowermost positions, as shown particularly in Fig. 4. It will be observed from Fig. 4 that when the anvil 4 is in its lowermost position, the top thereof is in substantial alignment with the bottom of the channel 24 and the opening 25 in the anvil guide 5. In this position the anvil 4 is ready to receive an upsettable member from the channel 24.

The alignment of the anvil 4 with the bottom of the channel 24 is determined by a stop 38 on the housing 12 for limiting the downward movement of the arm 39 of the follower 8. The stop 38 may be fixed or adjustable, as desired.

The piston 13 is provided on the opposite side to the piston rod 43 with another piston rod 44 projecting in the opposite direction from the piston rod 43. The piston rod 44 is in axial alignment with the plunger 33, and when the anvil 4 is in its uppermost or active position, the piston rod 44 is spaced from the plunger 33. However, as the anvil 4 is moving from its uppermost or active position to its lowermost position or that in alignment with the channel 24 and the opening 25, the piston rod 44 is closing the space between it and the plunger 33 so that at the moment the top of the anvil 4 comes into alignment with the bottom of the channel 24 and the opening 25 the piston rod 44 engages the plunger 33.

Continued movement of the piston rod 44 axially moves the plunger 33 to rock the rocker arm 31 about the pivot 32 to in turn move the feeding plunger 27 to move an upsettable member from the chute 26 into the channel 24 and another upsettable member from the end of the channel 24 into the anvil guide 5 and onto the top of the anvil 4. As soon as an upsettable member has been deposited on the top of the anvil 4, the extension 45 of the outer end of the plunger 33 engages and opens a push button valve 47 to exhaust air from the conduit 48 communicating therewith out of the port 49. This action results in the moving of the control valve (not shown) and of the type disclosed in the aforesaid patent applications, to admit compressed air from a source through the inlet 55 and the port 56 into the left end of the cylinder 14 to urge the piston 13, together with the piston rods 43 and 44 and the cam 10, to the left. As the cam 10 moves to the left, it engages the follower 8 to cam the same upwardly about the pivot 9 and to lift the anvil 4, through the fol-

lower 8, to its uppermost or active position, as shown in Fig. 1. A new upsettable member 40 is then disposed in position to receive the work and to permit the upsetting operation to be repeated. It is preferred that the upsettable members 40 and the anvil 4 have substantially the same diameter so that the sides of the anvil guide 5 guide the upsettable members 40 and hold them in exact alignment to be acted on by the set 3.

The plunger 33 has disposed thereabout a spring 57 bearing against a washer 58, held on the outer end of the plunger 33 by a pin 59, to yieldingly urge the plunger 33 to the left to return the rocker arm 31 and the plunger 27 to their positions, as shown in Fig. 1. As the plunger 27 moves to the right, it permits another upsettable member to slide down the chute 26 into position to be moved by the plunger 27 into the channel 24 during the next cycle of operation.

It will be apparent from the foregoing specification that the operation of my machine is semi-automatic in that a single manual actuation results in the retracting of the anvil 4 to its lowermost position, the disposal of an upsettable member 40 thereon, and the returning of the anvil 4 to its uppermost or active position without any further manual control. It will also be clear that while the invention is disclosed as applied to a vertically reciprocating anvil, it could also be equally as well applied to an anvil having a horizontal movement into and out of operative relation with the set 3. As shown in Figs. 2 and 3 particularly, the frame 1 is comprised of two spaced vertical members, between which the housings 12 and 29 are disposed. While this form of frame construction has been found to be very desirable, yet it is to be understood that the invention is not limited to this particular form of arrangement. Also, equivalent lost motion constructions may be substituted for that disclosed between the plunger 33 and piston rod 44. For instance, the piston rod 44 could be employed to positively return the plunger to its leftward position rather than the spring 57.

Having thus described my invention, what I desire to claim and secure by Letters Patent is:

1. A machine of the character described, comprising a set, means to operate said set, an anvil movable into and out of operative relation with said set, an anvil guiding member having a slideway along which said anvil moves, a channel for feeding upsettable members communicating with said slideway, means to reciprocate said anvil in said slideway into and out of operative relation with said set, said anvil in its retracted position being substantially in alignment with the bottom of said channel, means to feed a single upsettable member from said channel onto said anvil, and a lost motion delayed action connection between said anvil moving means and said feeding means to operate the latter whereby when said anvil reaches its retracted position said connection becomes effective to actuate said feeding means to feed an upsettable member from said channel onto said anvil.

2. A machine of the character described, comprising a set, means to operate said set, an anvil movable into and out of operative relation with said set, a channel for feeding upsettable members onto said anvil, means to reciprocate said anvil into and out of operative relation with said set, said anvil in its retracted position being substantially in alignment with the bottom of said channel, means to feed a single upsettable

member from said channel onto said anvil, and a lost motion delayed action connection between said anvil moving means and said feeding means to operate the latter whereby when said anvil reaches its retracted position said connection becomes effective to actuate said feeding means to feed an upsettable member from said channel onto said anvil.

3. A machine of the character described, comprising a set, means to operate said set, an anvil movable into and out of operative relation with said set, a channel for feeding upsettable members onto said anvil, means to reciprocate said anvil into and out of operative relation with said set, said anvil in its retracted position being substantially in alignment with the bottom of said channel, a source of upsettable members communicating with said channel, means to feed a single upsettable member from said source into said channel and at the same time another upsettable member from said channel onto said anvil, and a lost motion delayed action connection between said anvil moving means and said feeding means to operate the latter, whereby when said anvil reaches its retracted position said connection becomes effective to actuate said feeding means to feed an upsettable member into said channel from said source and another upsettable member from said channel onto said anvil.

4. A machine of the character described, comprising a set, means to operate said set, an anvil movable into and out of operative relation with said set, an anvil guiding member having a slideway along which said anvil moves, a channel for feeding upsettable members communicating with said slideway, means to reciprocate said anvil in said slideway into and out of operative relation with said set, said anvil in its retracted position being substantially in alignment with the bottom of said channel, a source of upsettable members communicating with said channel, means to feed a single upsettable member from said source into said channel and another upsettable member from said channel onto said anvil, and a lost motion delayed action connection between said anvil moving means and said feeding means to operate the latter, whereby when said anvil reaches its retracted position said connection becomes effective to actuate said feeding means to feed an upsettable member from said source into said channel and another upsettable member from said channel onto said anvil.

5. A machine of the character described, comprising a set, means to operate said set, an anvil movable into and out of operative relation with said set, an anvil guiding member having a slideway along which said anvil moves, a channel for feeding upsettable members communicating with said slideway, means to reciprocate said anvil in said slideway into and out of operative relation with said set, said anvil in its retracted position being substantially in alignment with the bottom of said channel, a source of upsettable members communicating with said channel, means to feed a single upsettable member from said source into said channel and at the same time another upsettable member from said channel onto said anvil, means yieldingly urging said last named means out of feeding relation, and a lost motion connection between said anvil moving means and said feeding means to overcome the action of said yieldable means and to actuate said feeding means to feed, when said anvil

reaches its retracted position, an upsettable member into said channel from said source and another upsettable member from said channel onto said anvil.

5 6. A machine of the character described, comprising a set, means to operate said set, an anvil movable into and out of operative relation with said set, a channel for feeding upsettable members onto said anvil, means to reciprocate said anvil into and out of operative relation with said set, said anvil in its retracted position being substantially in alignment with the bottom of said channel, means to feed a single upsettable member from said channel onto said anvil, 10 yieldable means urging said feeding means out of feeding relation with said channel, and a lost motion connection between said anvil moving means and said feeding means to overcome said yieldable means and to operate said feeding means, whereby when said anvil reaches its retracted position said connection becomes effective to actuate said feeding means to feed an upsettable member from said channel onto said anvil.

25 7. A machine of the character described, comprising a set, means to operate said set, an anvil movable into and out of operative relation with said set, a channel for feeding upsettable members onto said anvil, means to reciprocate said anvil into and out of operative relation with said set, said anvil in its retracted position being substantially in alignment with the bottom of said channel, means to feed a single upsettable member from said channel onto said anvil, yieldable means urging said feeding means out of feeding relation with said channel, a lost motion connection between said anvil moving means and said feeding means to overcome said yieldable means and to operate said feeding means, 30 whereby when said anvil reaches its retracted position said connection becomes effective to actuate said feeding means to feed an upsettable member from said channel onto said anvil, and means to replenish the supply of upsettable members in said channel.

45 8. A machine of the character described, comprising a vertically movable set, means to operate said set, a vertically movable anvil movable into and out of operative relation with said set, an anvil guiding member having a vertical slideway through which said anvil moves, a channel for feeding upsettable members communicating with said slideway, means to reciprocate said anvil in said slideway into and out of operative relation with said set, said anvil in its retracted position being substantially in alignment with the bottom of said channel, means to feed a single upsettable member from said channel onto said anvil, and a lost motion delayed action connection between said anvil moving means and said feeding means to operate the latter, whereby when said anvil reaches its retracted position said connection becomes effective to actuate said feeding means to feed an upsettable member onto said anvil.

55 9. A machine of the character described, comprising a set, means to operate said set, an anvil movable into and out of operative relation with said set, an anvil guiding member having a slideway along which said anvil moves, a channel for feeding upsettable members communicating with said slideway, means to reciprocate said anvil in said slideway into and out of operative relation with said set, said anvil in its retracted position being substantially in alignment with the bot-

tom of said channel, a source of upsettable members communicating with said channel, means to feed a single upsettable member from said source into said channel and at the same time another upsettable member from said channel onto said anvil, and a lost motion delayed action connection between said anvil moving means and said feeding means, in one position thereof to move said feeding means out of feeding relation and in another position thereof to actuate said feeding means when said anvil reaches its retracted position to feed an upsettable member into said channel from said source and another upsettable member from said channel onto said anvil.

10. A machine of the character described, comprising a set, means to operate said set, an anvil movable into and out of operative relation with said set, an anvil guiding member having a slideway along which said anvil moves, a channel for feeding upsettable members communicating with said slideway, a fluid operated piston to reciprocate said anvil in said slideway into and out of operative relation with said set, said anvil in its retracted position being substantially in alignment with the bottom of said channel, a source of upsettable members communicating with said channel, means to feed a single upsettable member from said source into said channel and at the same time another upsettable member from said channel onto said anvil, and a lost motion connection between said piston and said feeding means, in one position thereof to move said feeding means out of feeding relation and in another position thereof to actuate said feeding means when said anvil reaches its retracted position to feed an upsettable member into said channel from said source and another upsettable member from said channel onto said anvil.

11. A machine of the character described comprising a set, means to operate said set, an anvil movable into and out of operative relation with said set, an anvil guiding member having a slideway along which said anvil moves, a channel for feeding upsettable members communicating with said slideway, a cam for reciprocating said anvil in said slideway into and out of operative relation with said set, a fluid actuated piston for operating said cam, said anvil in its retracted position being substantially in alignment with the bottom of said channel, a source of upsettable members communicating with said channel, means to feed a single upsettable member from said source into said channel and at the same time another upsettable member from said channel onto said anvil, means yieldingly urging said last named means out of feeding relation, and a lost motion connection between said anvil and said piston to overcome the action of said yieldable means and to actuate said feeding means when said anvil reaches its retracted position to feed an upsettable member into said channel from said source and another upsettable member from said channel onto said anvil.

12. A machine of the character described, comprising a set, means to operate said set, an anvil movable into and out of operative relation with said set, an anvil guiding member having a slideway along which said anvil moves, a channel for feeding upsettable members communicating with said slideway, a cam for reciprocating said anvil in said slideway into and out of operative relation with said set, a fluid actuated piston for operating said cam, said anvil in its retracted position being substantially in alignment

with the bottom of said channel, a source of upsettable members communicating with said channel, means to feed a single upsettable member from said source into said channel and at the same time another upsettable member from said channel onto said anvil, a movable member for actuating said feeding means, a piston rod projecting from said piston, and a lost motion connection between said piston rod and said movable member, in one position to move said feeding means out of feeding relation, and in another position to actuate said feeding means when said anvil reaches its retracted position, to feed an upsettable member into said channel from said source and another upsettable member from said channel onto said anvil.

13. A machine of the character described, comprising a set, means to operate said set, an anvil movable into and out of operative relation with said set, an anvil guiding member having a slideway along which said anvil moves, a channel for feeding upsettable members communicating with said slideway, a cam for reciprocating said anvil in said slideway into and out of operative relation with said set, a fluid actuated piston for operating said cam, said anvil in its retracted position being substantially in alignment with the bottom of said channel, a source of upsettable members communicating with said channel, means to feed a single upsettable member from said source into said channel and at the same time another upsettable member from said channel onto said anvil, a movable member for operating said feeding means, means resiliently urging said feeding means out of feeding relation, and a piston rod projecting from said piston, said piston rod being in alignment with said movable member and spaced therefrom when said anvil is in active position, said piston rod being movable when said piston moves to retract said anvil to close the space between it and said movable member and then to actuate said movable member to actuate said feeding means to feed an upsettable member into said channel from said source and another upsettable member from said channel onto said anvil.

14. A machine of the character described, comprising a set, means to operate said set, an anvil movable into and out of operative relation with said set, an anvil guiding member having a slideway along which said anvil moves, a channel for feeding upsettable members communicating with said slideway, means to reciprocate said anvil in said slideway into and out of operative relation with said set, said anvil in its retracted position being substantially in alignment with the bottom of said channel, means to feed a single upsettable member from said channel onto said anvil, a movable member to actuate said feeding means, means to yieldingly urge said feeding means out of feeding relation, and a member projecting from said anvil reciprocating means, said projecting member being in alignment with said movable member and spaced therefrom when said anvil is in its active position, said projecting member being movable when said anvil reciprocating means moves to retract said anvil to close the space between it and said movable member and then to engage said movable member to actuate said feeding means to feed an upsettable member from said channel onto said anvil.

15. A machine of the character described, comprising a set, means to operate said set, an anvil movable into and out of operative relation

with said set, a channel for feeding upsettable members onto said anvil, means to reciprocate said anvil into and out of operative relation with said set, said anvil in its retracted position being substantially in alignment with the bottom of said channel, means to feed a single upsettable member from said channel onto said anvil, a movable member for actuating said feeding means, yieldable means for moving said feeding means out of feeding relation, and a member projecting from said anvil reciprocating means, said projecting member being in alignment with and spaced from said movable member when said anvil is in active position, said projecting member being movable when said anvil is moved from its active to its retracted position to close the space between said projecting member and said movable member and then to engage said movable member to actuate said feeding means to feed an upsettable member from said channel onto said anvil.

16. A machine of the character described, comprising a set, means to operate said set, an anvil movable into and out of operative relation with said set, an anvil guiding member having a slideway along which said anvil moves, a channel for feeding upsettable members communicating with said slideway, a cam follower for actuating said anvil into and out of operative relation with said set, a cam for coacting with said cam follower to actuate the same, a fluid actuated piston for actuating said cam, said anvil in its retracted position being substantially in alignment with the bottom of said channel, a source of upsettable members communicating with said channel, means to feed a single upsettable member from said source into said channel and at the same time another upsettable member from said channel onto said anvil, means yieldingly urging said last named means out of feeding relation, and a lost motion connection between said feeding means and said piston to overcome the action of said yieldable means and to actuate said feeding means, when said anvil reaches its retracted position, to feed an upsettable member into said channel from said source and another upsettable member from said channel onto said anvil.

17. A machine of the character described, comprising a set, means to operate said set, an anvil movable into and out of operative relation with said set, an anvil guiding member having a slideway along which said anvil moves, a channel for feeding upsettable members communicating with said slideway, a cam follower for actuating said anvil into and out of operative relation with said set, a cam for coacting with said cam follower to actuate the same, a fluid actuated piston for actuating said cam, said anvil in its retracted position being substantially in alignment with the bottom of said channel, a source of upsettable members communicating with said channel, means to feed a single upsettable member from said source into said channel and at the same time another upsettable member from said channel onto said anvil, means yieldingly urging said last named means out of feeding relation, a movable member to actuate said feeding means, and a piston rod projecting from said piston, said piston rod being in alignment with said movable member and spaced therefrom when said anvil is in active position, said piston rod being movable when said piston moves to retract said anvil to close the space

between it and said movable member and then to actuate said movable member to actuate said feeding means to feed an upsettable member into said channel from said source and another upsettable member from said channel onto said anvil.

18. A machine of the character described, comprising a vertically movable set, means to operate said set, a vertically movable anvil movable into and out of operative relation with said set, an anvil guiding member having a vertical tubular slideway through which said anvil moves, said tubular slideway being substantially the same in cross-section as said anvil, a channel for feeding upsettable members communicating with said slideway below the top thereof, means to reciprocate said anvil in said slideway into and out of operative relation with said set, said anvil in its retracted position being substantially in alignment with the bottom of said channel, means to feed a single upsettable member from said channel onto said anvil, and a lost motion delayed action connection between said anvil moving means and said feeding means to operate the latter, whereby when said anvil reaches its retracted position said connection becomes effective to actuate said feeding means to feed an upsettable member onto said anvil, said upsettable member being guided by said slideway when said anvil moves upwardly.

19. A machine of the character described, comprising a set, means to operate said set, an anvil movable into and out of operative relation with said set, a channel for feeding upsettable members onto said anvil, means to reciprocate said anvil into and out of operative relation with said set, said anvil in its retracted position being substantially in alignment with the bottom of said channel, a rocker arm pivoted between its ends, feeding means connected to one end of said rocker arm for feeding a single upsettable member from said channel onto said anvil, and a connection between said anvil reciprocating means and the other end of said rocker arm for actuating said feeding means to feed an upsettable member from said channel onto said anvil.

20. A machine of the character described, comprising a set, means to operate said set, an anvil movable into and out of operative relation with said set, a channel for feeding upsettable members onto said anvil, means to reciprocate said anvil into and out of operative relation with said set, said anvil in its retracted position being substantially in alignment with the bottom of said channel, a rocker arm, feeding means connected to one end of said rocker arm pivoted between its ends to feed a single upsettable member from said channel onto said anvil, a movable member to actuate said rocker arm to feed an upsettable member, means to yieldingly urge said feeding means out of feeding relation, and a member projecting from said anvil reciprocating means, said projecting member being in alignment with said movable member and spaced therefrom when said anvil is in its active position, said projecting member being movable when said anvil reciprocating means moves to retract said anvil to close the space between it and said movable member and then to engage said movable member to actuate said feeding means to feed an upsettable member from said channel onto said anvil.

LOYD A. WARD.
